ATTORNEY

UNITED STATES PATENT OFFICE.

FREDERICK RAPP, OF CHICAGO, ILLINOIS.

DESIGN FOR A WATCH-CASE.

SPECIFICATION forming part of Design No. 17,109, dated February 8, 1887.

Application filed October 18, 1886. Serial No. 216,593. Term of patent 11 years.

To all whom it may concern:

Be it known that I, FREDERICK RAPP, a citizen of the United States, residing at Chicago, in the county of Cook and State of Illinois, have invented a new and original Design for Watch-Cases, which is fully set forth in the following specification, reference being had to the accompanying drawings, forming a part hereof, and in which—

10 Figure 1 is a side view of my newly-designed watch-case, showing the same closed; and Fig. 2 shows the same view with the cover of the case open.

15 In this design is shown the head and breast of a lion gardant, with the rear part of the body formed of a dragon or serpent having its tail coiled.

No line showing the outline of the cover is

shown in Fig. 1, as it is to be so constructed as not to show such line.

The leading feature of my design consists of a flat watch-case, showing the fore part of a lion-like creature gardant, and having the rear part of the body in the shape of a curled dragon's tail.

What I claim is—

The design for a watch-case herein shown and described, the same consisting of a watch-case the front flat face of which has the shape of the fore part of a lion-like creature gardant, the rear part of the body thereof passing into the shape of a curled dragon's tail, as set forth.

FREDERICK RAPP.
